UNITED STATES PATENT OFFICE.

THOMAS E. VINESKI, OF TROY, PENNSYLVANIA.

DOUBLE ENVELOP.

1,184,282.

Specification of Letters Patent.

Patented May 23, 1916.

Application filed May 15, 1915. Serial No. 28,400.

To all whom it may concern:

Be it known that I, THOMAS E. VINESKI, a citizen of the United States, residing at Troy, in the county of Bradford and State 5 of Pennsylvania, have invented certain new and useful Improvements in Double Envelops; and I do hereby declare the following to be a full, clear, and exact description of the invention, such as will enable others 10 skilled in the art to which it appertains to make and use the same.

This invention relates to double envelops, made from a single piece of paper of the required character, and the principal object 15 of the invention is to provide an envelop which can be used for sending out samples, for advertising purposes, for filing away various small articles, for use as a collection envelop, and for many other purposes, said 20 envelop adapted to be folded, with the envelops at each end of the blank folded inside, and the entire device connected together by means of a cord or band.

The foregoing and other objects may be 25 attained by means of the construction illustrated in the accompanying drawings, in which

Figure 1 is a plan view of the paper blank for forming a double envelop. Fig. 2 is a 30 plan view showing one portion of one of the envelops folded over on the blank, Fig. 3 is a plan view showing one of the envelops completely folded, and the other in the process of folding, Fig. 4 is a longitudinal sectional view taken on the line 4—4 of Fig. 3, and Fig. 5 is a transverse sectional view taken on the line 5—5 of Fig. 3.

Referring to the drawings, the numeral 1 designates the paper webbing which 40 connects the two envelops, and on this paper may be printed any suitable advertisement relating to the class of goods to be inclosed within the envelops as samples or any other character of advertising. At opposite ends 45 of the paper blank portion 1 are envelops of like construction, and hence the description of one will answer for both, said envelops being merely reversed on the opposite ends of the blank but made of the same 50 general construction and form.

The envelop at each end of the blank comprises the body portion 2 having a slit 3

cut therefrom, said slit being substantially the shape of a sealing flap. Projecting from each side of the body portion 2 of the envelop is a side flap 4 adapted to be folded on the dotted line 5. At the end of the blank is a bottom flap 6 adapted to be folded on the dotted line 7. In folding the envelop, the paper is first folded on the line 8, as shown in Fig. 2. The flap 9 is then folded outwardly, as shown in Fig. 3. The body portion 2 of the envelop is connected by means of the adhesive substance 10, thus covering the aperture 11 which is formed by cutting out the flap 9. It is to be noted that the paper at the point 12 is left ungummed, as shown in Fig. 1 of the drawing. After the envelop has been folded as shown in Fig. 2 of the drawings the 70 side flaps 4 are folded over toward the center, and the flap 6 is folded on the line 7, and connected by the adhesive strips 13 to the side flaps 4, when the sealing flap 9 is gummed down on top of the flap 6 by 75 means of the adhesive substance 14, as shown more clearly at the right end of Fig. 3.

At the folded ends of the envelop, fastening disks 15 are secured by means of a suitable rivet or eyelet 16 and when the envelop 80 is folded centrally, both envelops are inside, and a cord or string may be connected to the disks 15 for holding the envelops closed.

From the foregoing it will be obvious that the two envelops at opposite ends of the 85 blank are readily accessible after the blank has been opened out, and that such an envelop is capable of many uses, can be manufactured at comparatively low cost, provides a very useful double envelop for many uses 90 in commercial lines as well as for church collections, for filing away articles or papers, and for many other uses.

Various changes may be made in the details of construction without departing from 95 the spirit and scope of the invention as defined in the claim.

What is claimed is:—

A double envelop comprising a paper blank and having a central connecting web, 100 said blank provided at opposite ends with side flaps, a bottom flap, a sealing flap provided in the central portion of each envelop, adhesive material on one face of the connect-

ing flap adjacent each end thereof, each of said envelops when assembled to have their side flaps folded inwardly, the bottom flap connecting the side flaps together, and the 5 sealing flap secured down over the bottom flap, said envelops being folded together inclosing both of the envelops inside the blank, and means on the opposite ends of

the folded portion of each of said envelops securing the same together.

In testimony whereof I affix my signature in presence of two witnesses.

THOMAS E. VINESKI.
